CLAIM

The ornamental design for a tray valve cover, as shown and described.

DESCRIPTION

FIG. 1 is a top perspective view of a tray valve cover showing our new design;

FIG. 2 is a bottom perspective view of the tray valve cover shown in FIG. 1;

FIG. 3 is a rear elevation view of the tray valve cover shown in FIGS. 1 and 2;

FIG. 4 is a left side elevation view of the tray valve cover shown in FIGS. 1-3, with the right side elevation view being a mirror image thereof;

FIG. 5 is a front elevation view of the tray valve cover shown in FIGS. 1-4;

FIG. 6 is a top plan view of the tray valve cover shown in FIGS. 1-5; and,

FIG. 7 is a bottom plan view of the tray valve cover shown in FIGS. 1-6.

The portions of the tray valve cover shown in broken lines are for illustrative purposes only and form no part of the claimed design.
